J. S. & W. B. Buell,

Cotton Press.

No 84,408.

Patented Nov. 24, 1868.

United States Patent Office.

JONATHAN S. BUELL, OF BUFFALO, AND WILLARD B. BUELL, OF POMPEY, NEW YORK.

Letters Patent No. 84,408, dated November 24, 1868.

IMPROVED SCREW-PRESS.

The Schedule referred to in these Letters Patent and making part of the same.

To all whom it may concern:

Be it known that we, JONATHAN S. BUELL, of Buffalo, in the county of Erie, and State of New York, and WILLARD B. BUELL, of Pompey, in the county of Onondaga, and State of New York, have invented certain new and useful Improvements in Screw-Press; and we do hereby declare that the following is a full, clear, and exact description thereof, reference being had to the accompanying drawings, making a part of this specification.

The nature of our invention consists—

First, in operating the pressure-screw of a cider, hay, or other press, by means of a ratchet-wheel and ratchet-lever, attached to said screw, in combination with a driving-crank and pitman, so that the continuous circular motion of the crank will impart a vibratory motion to the lever, and an intermittent rotary motion to the screw, thereby causing said screw to perform its function of moving the follower of such press or presses.

Second, in supporting the overhanging end of the ratchet-lever by means of a diagonal brace, connecting to the tail of the press-screw by a journal-bearing, which will not interfere with the free revolution of the screw, so that the screw may work up and down through its nut, without the brace coming in conflict therewith.

Third, in a special construction of the spring-pawl, by which the engagement of the ratchet-lever and ratchet-wheel is effected.

In the accompanying drawings—

Figure I is a side elevation of a press, with our improvements applied thereto;

Figure II is a plan of same;

Figure III is a plan of ratchet-lever, ratchet-wheel, and spring-pawl, on an enlarged scale; and

Figure IV is a longitudinal section of same.

Like letters refer to like parts in each of the figures.

A A represent the side posts, and B B', the bottom and top cross-heads of a press-frame, of common construction, the side posts being longitudinally grooved, to receive the follower C, and guide the same in its up-and-down movement.

D represents the press-screw, passing through a nut connected to the upper cross-head B', the lower end of said screw bearing upon the centre of the follower, or upon an iron step attached thereto, and so connected that, while turning freely, it may move the follower either up or down.

E represents the ratchet-wheel, which is firmly keyed to the head of the screw, just above the follower, and F is the ratchet-lever, hinged upon the screw-head, just below the ratchet-wheel.

In the present instance this lever is made partly of iron, and partly of wood, the wooden portion, F¹, being inserted in a socket, F², formed at the end of the iron portion. This construction is adopted as being lighter and less costly than an all iron one.

G is the ratchet-pawl, placed upon the upper side of the lever F, and engaging with the teeth of the ratchet-wheel.

The joint-bolt or pin upon which the pawl works is shown at g¹. The pawl is made double, that is to say, it has two points, g² and g³, equidistant from a line passing through the centre of the ratchet and said joint-pin, either of which points may be made to engage the teeth of the ratchet-wheel.

The location of the joint-pin, with reference to the points g² and g³, is such that lines tangent to the ratchet-wheel at the said points will pass inside of said joint-pin, so that the secure hold of either of said points, when engaged with the ratchet-teeth, is insured.

The pawl has an arm, h, extending on the opposite side of the joint-pin from the points g² and g³, the end of which arm has a triangular point, h.

A spring-pin, i, with a triangular point, is inserted in a socket, cast on the upper side of the ratchet-lever, as shown at i', said pin being in line with the joint-pin g¹ and the centre of the ratchet-wheel, so that, when one side of its triangular point is in contact with the opposite side of the triangular point of the pawl-arm h, it will throw one of the pawl-points into engagement with the ratchet-teeth, and when the other side of its triangular point is in contact with the opposite angular side of the pawl-arm, it will throw the other pawl-point into engagement with the ratchet-teeth.

A vibratory motion being imparted to the ratchet-lever, it will be communicated to the screw by the engagement of the pawl with the ratchet-wheel, and the direction in which the screw will turn may be governed at pleasure by the use of one or the other of the pawl-points.

When the triangular points of both pawl-arm and spring-pin are brought in line, neither of the pawl-points will engage the ratchet-teeth, and motion will not be imparted to the screw.

A handle, J, is projected from the pawl, by which the pawl may be readily set in either of its three positions.

K represents the crank-shaft, to which the motive-power, either hand, steam, horse, or other power, is applied.

It is supported in proper journal-bearings in standards K', and parallel with the ratchet-lever, when the same is at the middle of its vibration.

L represents the pitman, connecting the crank L' with the end of the ratchet-lever, so that the revolution of the crank will communicate a vibratory motion to said lever.

This pitman should be of sufficient length to prevent its action being materially affected, by reason of the ratchet-lever moving up and down with the screw.

The diagonal brace M leads from the end of the ratchet-lever to the top of the press-screw, and connects therewith by a journal-bearing, which allows it to vibrate freely while it sustains its weight.

In presses employing two or more screws, a ratchet-wheel, pawl, and lever should be provided for each screw, when, by the use of a connecting-rod between the ends of said levers, they may be operated, and motion imparted to all the screws simultaneously.

Our invention will greatly facilitate the operation of screw-presses of all kinds, and lessen the labor required. It is specially applicable to cider and wine-mills, and will meet a long-felt want for such purposes.

Having thus described our invention, What we claim, and desire to secure by Letters Patent, is—

1. The ratchet-wheel, lever, pitman, and crank, in combination with the press-screw, when arranged and

operated substantially as and for the purpose set forth.

2. The combination of the diagonal brace **M** with the oscillating lever **F** and screw **D**, arranged so as to support the former, and permit the necessary movement of the parts, as set forth.

3. The combination of the triangular-pointed spring-pin **i** and arm **h** with the double-pointed pawl **G**, arranged to operate substantially as and for the purpose set forth.
